APPARATUS FOR MAKING SHEET METAL

Raymond J. Wean and Donald A. McArthur,
Warren, Ohio, assignors to The Wean Engineering Co., Inc., Warren, Ohio, a corporation of Ohio

Application June 1, 1938, Serial No. 211,215

1 Claim. (Cl. 51—9)

This invention relates to apparatus employed in the manufacture of sheet metal and, in particular, to the control of the abrasive material utilized to prepare hot rolled steel strip for reduction to final gauge by cold rolling.

In Wean Patent No. 2,120,318, there is disclosed apparatus for the treatment of hot rolled strip including abrasive throwing mechanisms for cleaning the strip. It frequently becomes necessary to stop the strip travelling through this apparatus, for various purposes. Unless the abrasive blast is shut off when the strip is stopped, excessive abrasion of the latter will result. It has been the practice heretofore to control the abrasive blast manually by shutting off the supply of abrasive when strip is stopped. This arrangement is objectionable because it involves the human element and it sometimes happens that the supply of abrasive is not cut off when it should be.

We have invented an automatic control for the supply of abrasive to the throwing mechanisms such that the supply of abrasive is positively terminated whenever the movement of the strip through the several machines of the processing line is interrupted, even if only momentarily. In accordance with the invention, we provide an electro-pneumatic control system for a valve in the abrasive supply line extending to the centrifugal abrasive throwing mechanisms. This system is actuated by means responsive to the movement of the strip through the processing line, for example a centrifugal switch actuated by one of the sets of pinch rolls used to forward the strip through the line.

Our invention is described in greater detail hereinafter, with reference to the drawing illustrating diagrammatically a preferred arrangement of the apparatus.

The single figure of the drawing is a diagrammatic view showing only the essential elements of the invention, with parts in section.

While our invention is applicable generally to various types of abrading apparatus, it is intended particularly for use in connection with strip cleaning equipment of the type incorporating centrifugal abrasive-throwing wheels or impellers W such as that shown in Peik Patent 1,953,566. This equipment may be embodied in the form shown generally in our Patent 2,120,318 above mentioned. As there shown, the apparatus includes motor-driven pinch rolls for drawing the strip through a cabinet in which the centrifugal wheels are journaled. After being discharged by the wheels, the abrasive is collected in a hopper

in the bottom of the cabinet and returned by suitable means to a storage hopper 10 from which it flows through a duct 11 to the wheels for repeated discharge against the strip. The duct 11 has a 5 shut-off valve 12 therein. The traction pinch-rolls are indicated at 13.

We provide means for closing the valve in the abrasive supply duct on stoppage of the strip passing through the cabinet, for any reason. This 10 prevents excessive abrasion of a portion of the strip in case it should be necessary to stop the movement of the latter at any time, for example, when stitching together the ends of successive strip lengths, or shearing them apart.

15 To accomplish this result, we employ a cylinder 18 having a piston 19 therein adapted to be operated by fluid under pressure contained in a suitable source 20 and controlled by a valve 21. The valve 21 is operated electromagnetically, an operating winding being shown at 22. A switch 23 is effective to close an energizing circuit for the winding 22 to operate the valve 21. When so operated, fluid under pressure is admitted to the right-hand end of the cylinder 18, whereas, the 25 other end is vented to the atmosphere. The resulting movement of the piston is effective through suitable mechanical connections, such as piston rod 24, link 25 and crank 26, to operate the valve 12 to closed position to shut off the supply of abrasive to the centrifugal impellers. The 30 reverse movement occurs on the opening of switch 23.

The switch 23 may be operated in any convenient manner, in accordance with the movement 35 of a strip through the cleaning apparatus, so long as the arrangement is such that the switch 23 will remain open while the strip continues to move but will be closed in the event of stoppage thereof. The switch 23 is preferably a centrifugal 40 switch mounted on the pinch rolls 13, and driven thereby, which remains open so long as the pinch rolls operate although other types of switches operating in accordance with movement of the strip may be employed as well. Since the 45 pinch rolls 13 furnish the traction for advancing the strip, their speed is proportional to the rate of feeding and furnishes an index as to the continuance of strip movement.

It will be apparent from the foregoing that, as 50 long as the strip is moving, i. e., so long as the pinch rolls are being driven, the switch 23 remains open and the valve 12 is held open, since the valve 21 tends to return to the illustrated position by gravity.

55 It will be readily appreciated that the inven-

tion is characterized by numerous advantages over the prior practice involving hand control of the abrasive supply. By means of the invention, the supply of abrasive material is cut off immediately on stoppage of the strip being processed and is resumed as soon as the strip starts to move again. In this way, uniform treatment of the entire length of strip is assured without variations which might otherwise result from continuation of the supply of abrasive after stoppage of the strip or delay in restarting the abrasive supply after the strip is started again.

Although we have illustrated and described but a preferred embodiment of the invention, it will be understood that many changes therein may be made within the terms of the following claim.

We claim:

Abrading apparatus comprising means for normally moving material to be abraded through the apparatus in a continuous manner, means for directing an abrasive blast onto the moving material, a valve controlling the supply of abrasive material to said blast-directing means, means actuated by fluid-pressure for operating the valve, electrical means controlling the fluid-pressure-actuated means, said electrical means including means actuated by the means for moving the material and effective on stoppage of the material-moving means to cause operation of the fluid-pressure actuated means, whereby said valve is actuated to interrupt the supply of abrasive material to said blast-directing means.
